(57) **CLAIM**

The ornamental design for a digital audio disc player for automobile, as shown and described.

DESCRIPTION

FIG. 1 is a perspective view of the front, left side and top plan of the invention.

FIG. 2 is a top plan view of the design according to the invention.

FIG. 3 is a front view of the design according to the invention.

FIG. 4 is a left side view of the design according to the invention.

FIG. 5 is a right side view of the design according to the invention.

FIG. 6 is a bottom view of the design according to the invention; and,

FIG. 7 is a rear view of the design according to the invention.

The elements shown in broken lines are for illustrative purposes only and form no part of the claimed design.

1 Claim, 4 Drawing Sheets
